UNITED STATES PATENT OFFICE

JAMES R. MOFFATT, OF CHICAGO, ILLINOIS, ASSIGNOR TO UNION SPECIAL MACHINE COMPANY, OF CHICAGO, ILLINOIS, A CORPORATION OF ILLINOIS

THREAD-CONTROLLING MECHANISM FOR SEWING MACHINES

Application filed August 29, 1928. Serial No. 302,809.

The invention relates to new and useful improvements in thread controlling mechanisms for sewing machines, and more particularly to the thread guiding mechanism used in connection with a rotary thread controlling element.

An object of the invention is to provide a thread guiding mechanism used in conjunction with a rotary thread controlling element having laterally projecting thread engaging cam faces, which thread guiding mechanism includes open thread eyes so that said thread guides may be readily threaded without moving the same to render them accessible.

A further object of the invention is to provide a thread guiding mechanism of the above type wherein the thread guides and the cast-off are all mounted on one supporting member adapted to be adjusted in a direction circumferentially of the axis of rotation of the thread controlling element.

In the drawings:

Figure 1 is a plan view of a portion of a sewing machine embodying the improvements.

Fig. 2 is a sectional view on the line 2-2 through a portion of the thread controlling element and showing the supporting bracket for the thread guides and cast-off in edge view.

Fig. 3 is a sectional view on the line 3-3 of Fig. 1.

Fig. 4 is a perspective view of the supporting segment for the thread guides showing the thread guides and the cast-off and strip per mounted thereon.

The invention is directed to a thread controlling mechanism of the type wherein there is a rotating thread controlling element having laterally projecting cylindrical flanges radially spaced from each other and with their free edges shaped to provide thread take-up cams. Associated with this thread controller is a thread guiding mechanism which includes an outer thread guide located outside of the periphery of the thread controlling element, and an inner thread guide located inside of the periphery of the flanges. The inside thread guide is carried by a segment bracket and is provided with a projecting arm on which the outer thread guide is

mounted. On the arm carrying the outer thread guide the cast-off and thread retainer are mounted. Both the inner and the outer thread guides include eyes with a slot leading therefrom and the face of the supporting member for each thread guide is curved so that when the thread is laid against said curved faces and drawn on it will slide along both of the curved faces through the slots and into the eyes. Thus it is that the thread guiding mechanism is self-threading.

Referring more in detail to the drawings, the invention is shown as applied to a sewing machine having a cylindrical supporting member 1 in which is mounted a rotating shaft 2. This rotating shaft 2 carries the rotating thread controlling element 3. Said rotating thread controlling element 3 is provided with an outer cylindrical flange 4 and an inner cylindrical flange 5. These flanges are radially spaced from each other. The free edges of the flanges are cam shaped and these are the thread controlling cams which in succession engage the threads for taking up and giving up said threads. A sleeve 6 is mounted on the shaft and this sleeve is held from rotation with the shaft so that it is stationary. Attached to this sleeve is a segment bracket 7, which is secured to the sleeve by a screw 8 passing through a slot in the bracket and threaded into the sleeve. Thus it is that the segment bracket may be adjusted circumferentially on the sleeve about the center of the shaft.

Projecting outwardly from this segment bracket 7 is an arm 9. This arm 9 is provided with a thread eye 10 and a slot 11 leading to the eye. There is also a curved surface 12. Just beyond the eye from the curved surface 12 there is a shoulder 13. The thread engaging curved face 12 will slide along the same and pass through the slot 11 into the thread eye 10. Also attached to this arm 9 is a second arm 13a. This arm projects over the rotating controlling element while the arm 9 is inside thereof so that the thread eye 10 is radially disposed within the periphery of the inner thread controlling flange 5. The arm 13a is provided with a curved face 14 which leads into an

inclined slot 15. At the inner end of this slot 15 is a thread eye 16. This is the outer thread eye which forms the outer thread guide, and this thread eye is located beyond the periphery of the outer thread controlling flange 4. The thread is led from the supply through a guiding passage 16' and thence between the nipper springs 17. The thread is indicated at *l* in the drawings. After the 10 thread leaves the nipper springs if it is placed against the curved faces 12 and 14 and drawn toward the front of the machine it will slide along these curved surfaces and enter the eyes 10 and 16. Thus it is that the thread guides 15 are self-threading as all that is necessary is to lay the thread against the curved faces and pull on it and it will enter the eyes.

Attached to the arm 13^a is a forwardly projecting member 18, which is provided with a 20 straight face 19 lying in a plane at right angles to the axis of the shaft. Also carried by this projecting member 18 is a cast-off arm 20, which lies in the space between the cylindrical flanges controlling the thread. This 25 cast-off member engages the thread and casts it off from the cam faces, while the retainer 19 puts a slight drag on the thread and retards the thread as it is given up to the stitching element with which said controller is 30 associated. This thread controller with its cast-off and retainer per se form no part of the present invention. They are similar in mode of operation to the cast-off and retainer disclosed in my co-pending application Serial No. 130,954, filed August 23, 1926. The 35 present invention is directed particularly to the manner of mounting the thread guides and the construction thereof whereby they are self-threading.

It is obvious that minor changes in the 40 details of construction may be made without departing from the spirit of the invention as set forth in the appended claims.

Having thus fully described my invention, 45 what I claim as new and desire to secure by Letters Patent, is:—

1. A thread controller for sewing machines comprising a rotating shaft, a thread controlling element mounted on said shaft and having 50 a laterally projecting flange, thread guides located within and without the periphery of the flange, an arm for each thread guide, said arms extending laterally beyond the flange and connected at their outer ends, 55 each arm having a curved face leading through a slot to a guide eye forming the thread guide, and means for supporting said arms.

2. A thread controlling for sewing 60 machines comprising a rotating shaft, a thread controlling element mounted on said shaft and having a laterally projecting cylindrical flange, thread guides located within and without the periphery of the flange, an arm for 65 each thread guide extending laterally be-

yond the flange and connected at their outer ends, and a stationary supporting bracket to which the arm of the inner thread guide is connected, said arms having curved faces leading through slots to the guide eyes forming the thread guides. 70

3. A thread controller for sewing machines comprising a rotating shaft, a thread controlling element mounted on said shaft and having a laterally projecting cylindrical flange, thread guides located within and without the periphery of the flange, an arm for each 75 thread guide extending laterally beyond the flange and connected at their outer ends, a stationary supporting bracket to which the arm of the inner thread guide is connected, said arms having curved faces leading through slots to the guide eyes forming the thread guides, a member projecting from the arm carrying the outer thread guide, said member being disposed relative to the flange of the thread controlling element and shaped so as to provide a cast-off for casting the thread off from the controlling cam formed on said flange, and a retainer for retaining the thread 80 after it is cast from the controlling cam. 85

4. A thread controller for sewing machines comprising a rotating shaft, a threaded controlling element secured to the shaft and having radially spaced laterally projecting cylindrical flanges, thread guides located within and without the periphery of the flanges, a stationary sleeve on the shaft extending underneath the flanges, a segmental bracket secured to said stationary sleeve, an arm for 90 the inner thread guide rigidly connected to said bracket, and an arm for the outer thread guide attached to the arm for the inner thread guide at a point beyond said flanges, said arms having curved faces leading through slots to 95 eyes forming the thread guides whereby said thread guides are self-threading. 100

5. A thread controller for sewing machines comprising a rotating shaft, a thread controlling element secured to the shaft and having radially spaced laterally projecting cylindrical flanges, thread guides located within and without the periphery of the flanges, a stationary sleeve on the shaft extending underneath the flanges, a segmental bracket secured to said stationary sleeve, an arm for the inner thread guide rigidly connected to said bracket, an arm for the outer thread guide attached to the arm for the inner thread guide at a point beyond said flanges, said arms having curved faces leading through slots to 110 eyes forming the thread guides whereby said thread guides are self-threading, and a member secured to the arm carrying the outer thread guide, said member having a portion projecting between said flanges and provided with an inclined face for stripping the thread from the take-up cams formed on said flanges. 115

6. A thread controller for sewing machines comprising a rotating shaft, a thread control- 120 125 130

ling element secured to the shaft and having radially spaced laterally projecting cylindrical flanges, thread guides located within and without the periphery of the flanges, a stationary sleeve on the shaft extending underneath the flanges, a segmental bracket secured to said stationary sleeve, an arm for the inner thread guide rigidly connected to said bracket, an arm for the outer thread guide attached to the arm for the inner thread guide at a point beyond said flanges, said arms having curved faces leading through slots to eyes forming the thread guides whereby said thread guides are self-threading, and a member secured to the arm carrying the outer thread guide, said member having a portion projecting between said flanges and provided with an inclined face for stripping the thread from the take-up cams formed on said flanges, said member also having a thread retaining face adapted to cooperate with the flanges in the retaining of the thread after it is cast from the take-up cams.

In testimony whereof, I affix my signature.

JAMES R. MOFFATT.
